UNITED STATES PATENT OFFICE.

FREDERICK M. FURBER, OF REVERE, MASSACHUSETTS, ASSIGNOR TO UNITED SHOE MACHINERY CORPORATION, OF PATERSON, NEW JERSEY, A CORPORATION OF NEW JERSEY.

MACHINE FOR REPAIRING PATENT LEATHERS.

Application filed September 22, 1924. Serial No. 739,120.

This invention relates to machines for use in the manufacture of leather articles. The invention is illustrated as embodied in a machine designed for repairing imperfections in the finish of articles manufactured of patent or enameled leathers.

A machine of this character is disclosed in United States Letters Patent No. 1,096,423, granted May 12, 1914 on an application of 10 Frederick M. Furber, in which a novel construction is provided for working enamel or other repairing substance into the surface of the leather. The machine disclosed in said Letters Patent comprises a work-rubbing tool 15 arranged to have a work-rubbing movement in a closed elliptical path effected by simultaneously rocking the tool about its axis and imparting axial reciprocations to it. This compound movement of the work-rubbing member is highly desirable for the reason that it enables a more perfect distribution of the enamel and a nearer approach to the skill of an efficient operative than has been otherwise provided. When the machine is being 20 used for treating shoes, it is found that, as the operation approaches the sole edge, the transverse movement of the work-rubbing member, by reason of its axial reciprocations, sometimes causes the rubbing member to 25 vibrate against the sole, throwing the shoe away from the tool and preventing the most effective treatment of this area. This causes the repairing fluid to gather and harden in the crease, and unless care is taken, the adjacent surfaces may be poorly polished. Also, 30 the vibration which is imparted to the work by its contact with the sole edge has a tendency to be objectionable to the operators because they commonly hold the shoe against their breasts in order to give it proper bearing upon the work-rubbing member.

Accordingly, an object of this invention is to provide an improved machine by the use of which operations such as patent and 45 enamel leather repairing may be still further facilitated without sacrificing any of the advantages characteristic of machines of the type above referred to. This is accomplished in the illustrative embodiment of the invention by an organization having provision for dispensing with the axial reciprocations of the tool-carrying shaft at the will of the operator.

In the illustrated preferred construction,

in accordance with features of the invention, 55 the axial reciprocations of the tool shaft are imparted by mechanism comprising an eccentrically mounted roll driven from the drive shaft of the machine and normally disposed between and engaging the flanges of a 60 collar on the tool shaft and provision is made for rendering this mechanism ineffective as by the axial withdrawal of the eccentrically mounted roll to a point where it is no longer effective to reciprocate the tool shaft. Preferably, the flanges of the collar are beveled and the eccentric roll is in the form of a frustum of a cone. This arrangement allows the roll to be withdrawn sufficiently to accomplish the desired object without requiring 65 that it be withdrawn beyond the circle of the flanges themselves, thereby ensuring the re-entrance of the roll into the space between the flanges regardless of the relative position of the parts, when it is again desired to re- 70 ciprocate the tool shaft, the flanged collar being uniformly positioned by a spring and stop ready for this reengagement.

A more complete description of the invention is found in the following specification 80 taken in connection with the accompanying drawings in which:—

Fig. 1 is a perspective view, with parts broken away, of the head of my improved machine;

Fig. 2 is a side elevation of the same portion of the machine with the cover of the casing removed and parts shown in section;

Fig. 3 is a plan view of the mechanism for imparting axial reciprocation to the tool 90 shaft;

Fig. 4 is a fragmentary view showing these parts in inoperative position;

Fig. 5 is an end elevation, with parts broken away, of the head of the machine; and

Fig. 6 is a longitudinal section through the centers of the drive shaft and the jack shaft.

In the machine shown in the drawings, a round shoe-rubbing tool 10 is mounted upon a tool shaft 12 supported in a bearing 14 (Figs. 3 and 5) in the casing 16 of the head of the machine so that it may be rotated or reciprocated axially. A cloth cover 18 in the form of an endless strip tensioned by means of a spring-pressed fork 20 is provided for the 100 work-rubbing tool 10 and in the use of the machine a shoe is commonly held against the lower face of the tool 10. A drive shaft 22 of

the machine is mounted in suitable bearings in the casing 16 and positioned at right angles to the tool shaft 12 and overlies said tool shaft. Power may be supplied to the drive shaft by means of a pulley 24 adapted to be clutched to the shaft 22 by a clutch disk 26 which is normally held in engagement with the pulley 24 by means of a spring 28 which surrounds the shaft and presses against the hub of a gear 30. This gear is pinned to the drive shaft, and one end of its hub is halved at 32 to provide sliding engagement with a sleeve 34 upon which there is mounted an inclined grooved cam disk 36. Co-operating with the flanges of this inclined cam disk and arranged to slide the cam disk along the axis of the drive shaft is a part which, for convenience, may be termed an oscillator 40 having arms fitting between the flanges of the grooved disk 36 and a stud 42 rotatively mounted in a cross member 44 which in turn is journaled upon trunnions 46 supported by the casing 16. Whenever the grooved disk 36 is rotated by means of the halved joint 32, it is caused to move back and forth along the drive shaft, and this movement is imparted to a worm 50 formed upon a sleeve surrounding and frictionally engaging the sleeve 34 upon the shaft 22. The worm 50 constitutes a toothed member which is in mesh with a worm gear 52 splined upon the tool shaft 12. Formed integrally with the worm 50 is a spur gear 54 and the worm 50 and the spur gear 54 are maintained in engagement with the hub of the grooved disk 36 by a spring 55 (Fig. 2) seated in a recess formed in a stop collar 58 secured to the sleeve 34 and bearing upon a ball 57 which rests upon a disk 59 resting against the face of the spur gear 54. The spur gear 54 is arranged in toothed engagement with a gear 60 mounted on a stub shaft 62 and prevented normally from rotating by means of a thumb lever 64 which engages a stop 66 upon the casing. So long as the thumb lever 64 is kept in position to engage the stop 66, by a spring plunger 65 (Fig. 6), the friction between the drive shaft 22 and the sleeve on which the worm 50 and the spur gear 54 are formed will not be permitted to turn the worm 50. On the other hand, the worm 50 will be reciprocated along its axis by reason of being held in engagement with the oblique grooved cam disk 36, and this axial movement will effect an oscillatory movement of the worm gear 52 on the tool shaft and cause the tool to be rocked through the desired extent of movement. Inasmuch as the cloth cover 18 over the tool becomes soiled rather quickly, provision is made for rotating the tool at the will of the operator in order to bring a fresh portion of the cover into position for use, and this may be accomplished by depressing the thumb lever 64 and allowing one complete revolution of the gear 60. This will allow several

revolutions of the spur gear 54 and the worm 50 and will move the surface of the work-rubbing tool along about one inch.

At the same time that the tool shaft 12 is being given a rocking movement by the mechanism above described it may be axially reciprocated by other mechanism to impart the lateral movement, which, when combined with the rocking component already described results in a compound movement of the tool. These two movements may be compounded in various ways so that the resulting path of any operative point on the periphery of the tool is in the form of a circle, an ellipse or an elongated figure eight in contact with the work. The preferred mechanism which is herein illustrated is arranged to generate the figure eight movement. To this end the worm gear 52 is splined to the tool shaft 12 and is held against the bearing 14 (Fig. 3) by a spring 70 positioned between the worm gear 52 and the hub of a collar 72. The hub of this collar is recessed to have a sliding connection 74 with the complementally shaped parts of the hub of the worm gear 52 and the collar 72 is pinned to the tool shaft 12. Mounted for engagement between the flanges of the collar 72 is an eccentrically mounted roll 76 carried upon the end of a jack shaft 78 which is parallel to the drive shaft 22 and is supported in suitable bearings in the casing. The jack shaft 78 has a pinion 80 splined thereon, which is positioned in driving engagement with the gear 30 fixed on the drive shaft 22. The rotation of the gear 30 with the drive shaft will therefore be communicated to the eccentrically mounted roll 76 which, in turn, will impart axial reciprocations to the tool shaft 12 without disturbing the operative engagement of the toothed worm 50 and the gear 52. In order that such reciprocations may be discontinued at the will of the operator, means are provided for rendering the roll 76 ineffective by disconnecting the roll 76 from the collar 72, said means comprising a flanged collar 82 secured to the end of the jack shaft 78. An operator-controlled bell crank lever 84 carrying a roll 86, which engages between the flanges of the collar 82, is arranged to be operated by a treadle 87 so that the operator may cause the withdrawal of the eccentrically mounted roll 76 to inoperative position whenever it is desired. The eccentrically mounted roll 76 is normally maintained in engagement by a spring 88 connected to one arm of the bell crank lever and the casing of the machine, and this spring 88 holds the lever 84 against a stop 85 (Fig. 2) adjustably positioned in a removable side plate 16' forming part of the casing. This stop 85 thereby will determine the correct operating position of the roll 76 within the flanges of the collar 72. The eccentrically mounted roll 76 is secured to the jack shaft 78 by means of a head-

ed rod 90 passing through the jack shaft and secured by means of a nut 92 at the exposed end thereof. Attention is called to the fact that the flanges of the collar 72 are 5 beveled to coact with the conical shape of the roll 76, and, as is shown in Fig. 4, when the roll has been withdrawn to the full extent required for effective operation, its end still lies between the circles of the peripheries 10 of the flanges of the collar 72 without engaging them as it rotates. An adjustable stop 71 is provided in the side plate 16' against which the end of the tool shaft 12 carrying the collar 72 is thrown by the spring 70, upon 15 the withdrawal of the roll 76, so as to determine the endwise limiting position of the shaft and assist in the ready reengagement of the roll 76. When the treadle-operated lever 84 is released, the roll 76 will be sure to enter 20 the space between and to reengage the flanges of the collar 72 (properly positioned by the stop 71) so that it will again reciprocate the tool shaft axially. From Figs. 1 and 2 it will be seen that there is provided on the front 25 of the machine head a thumb screw 94 which is held from dropping out of the machine by a lug 96 and is arranged to bear against the end of the drive shaft 22 to compress the spring 28 and disconnect the clutch 26 from the pulley 24 when the operator wishes to stop 30 the machine.

It is preferred to arrange the gear 30 with twice as many teeth as the pinion 80. The jack shaft 78 will then revolve at twice the speed of the drive shaft, and since each revolution of the latter is accompanied by one complete axial reciprocation of the worm 50 and consequently one complete rotative oscillation of the tool shaft 12, it follows that 35 for every rotative oscillation of the tool shaft, two axial reciprocations thereof will occur. Thus it will be seen that the path of the tool is made up of two components at right angles to one another, the frequency of reciprocation of one component being twice as great as the frequency of the other component.

In order to obtain a properly shaped figure eight, it is necessary that, when one component is at an end of its stroke, the other component whose frequency is twice as great shall be at the middle of its stroke. It is therefore necessary to set the drive shaft 22 and the jack shaft 78 in such angular relationship that, when the worm 50 is at one limit of its horizontal movement, the eccentric roll will be midway between the limits of its horizontal movement. To aid in assembling the machine with the shafts 22 and 78 set in proper relation, a disk 98 is fixed 50 beside the gear 30 and is provided with a projection (not shown) arranged so that, unless the drive shaft and jack shaft are set in correct angular relationship, it will strike the hub of the pinion 80 and prevent continued rotation of the drive shaft. A de-

pression in the said hub, however, permits this projection to revolve without obstruction when the drive shaft and jack shaft are correctly set.

In the use of the machine, after the operator has applied a suitable quantity of repairing fluid, the shoe will be held against the rubbing tool 10 to which there is imparted in the particular machine illustrated a motion such that any operating portion of the 70 tool has a path of movement resembling an elongated figure eight in contact with the work, which combines a rocking movement and an axial reciprocation of the tool shaft. If in the course of the work the lateral movement of the tool becomes unnecessary or undesirable, it is only necessary for the operator to depress the treadle (not shown) attached to the bell crank lever 84, wherupon the tool will be rocked in a single plane. In order to 80 change the cloth cover (18) to provide a clean working position thereon, the operator may depress the thumb piece 64 to allow rotation of the gear 60 and the consequent partial rotation of the tool 10. The machine may be 85 completely stopped by screwing in the thumb screw 94.

Having described the invention, what I claim as new and desire to secure by Letters Patent of the United States is:

1. In a machine for repairing patent leather shoes, the combination of a drive shaft, a tool shaft, a jack shaft driven from said drive shaft, a work-rubbing tool, an operating portion of the periphery of which is arranged to have a compound movement in a closed path in rubbing contact with a piece of work, means including a toothed sleeve frictionally mounted on said drive shaft for oscillating said tool about its axis to produce one component of said compound rubbing movement, a releasable gear meshing with said toothed sleeve and permitting a progressive rotative movement of the tool at the will of the operator, means including a collar on said tool shaft provided with beveled flanges and an eccentrically mounted roll at the end of said driven jack shaft for simultaneously reciprocating said tool axially to produce another component of its compound rubbing movement, and means for moving said jack shaft endwise to withdraw said roll thereby to render the tool-reciprocating means ineffective to impart axial reciprocations to the tool at the will of the operator without interrupting the oscillations of the tool about its axis.

2. In a machine for repairing patent leather shoes, the combination of a round work-rubbing tool having an operating point on its periphery, means for oscillating said tool about its axis, means for simultaneously reciprocating said tool axially, to move the operating point in a closed path in contact with the work, releasable means permitting

- a progressive rotative movement of the tool at the will of the operator, and means for disconnecting the means for imparting axial reciprocations at the will of the operator.
5. In a machine for repairing patent leather shoes, the combination of a shoe rubbing tool, a shaft supporting said tool, a gear on said shaft, means including a toothed member co-operating with said gear to oscillate said shaft about its axis, means to reciprocate said shaft axially, without disturbing the operating engagement of said toothed member and said gear, and means to disconnect said means for imparting axial reciprocations at the will of the operator.
4. In a machine for repairing patent leather shoes, the combination of a tool, a shaft supporting said tool, a rotary drive shaft, a worm supported on said drive shaft but arranged to be normally held against rotation therewith, a worm gear mounted on said tool shaft and arranged to mesh with said worm, means operated by the rotary movement of said drive shaft axially to reciprocate said worm thereby to oscillate said tool shaft about its axis, a flanged collar on said tool shaft, a stop to determine one limiting, endwise position of the tool shaft, a spring urging said shaft with its collar against the stop, rotatable means adapted to engage the flanges of said collar and operated by the rotary motion of said drive shaft to reciprocate said tool shaft axially against the action of said spring, and operator controlled means for removing said rotatable means from engagement with the flanged collar constructed and arranged to allow the immediate reengagement of the rotatable means and the collar.
40. 5. In a machine for repairing patent leather shoes, the combination of a shoe rubbing tool, a shaft supporting said tool, a gear mounted on said shaft arranged to impart angular shoe rubbing movements to said tool and shaft while allowing axial reciprocations of the shaft with respect to the gear, a drive shaft at right angles to the tool shaft, means on the drive shaft for imparting angular movements to the gear to turn the tool shaft, a grooved collar on said tool shaft having flanges, a jack shaft parallel to the drive shaft and geared thereto, an eccentrically mounted roll at the end of the jack shaft engaging the flanges of said collar and arranged to impart axial reciprocations in opposed directions to the tool shaft which combine with the angular movements to produce compound work rubbing movements, means for withdrawing said roll from engagement with said collar, and means for positioning said flanged collar endwise in a predetermined location when it is no longer reciprocated by the roll thereby to facilitate re-engagement of the roll between the flanges of the collar.
6. In a machine of the class described, the combination of a tool, a shaft supporting said tool, a gear mounted on said shaft arranged to impart turning movement thereto while allowing axial reciprocations of the shaft with respect to the gear, means for imparting rotative movements to the gear to turn the shaft, a collar on said shaft provided with beveled flanges, and an eccentrically mounted, driven, frusto-conical roll adapted to engage the flanges of said collar and impart axial reciprocations to said tool shaft.
7. In a machine of the class described, the combination of a tool, a shaft supporting said tool, a gear mounted on said shaft arranged to impart turning movement thereto while allowing axial reciprocation of the shaft with respect to the gear, means for imparting rotative movements to the gear to turn the shaft, a collar on said shaft provided with beveled flanges, an eccentrically mounted, driven, frusto-conical roll adapted to engage the flanges of said collar and impart axial reciprocations to said tool shaft, and means for withdrawing said frusto-conical roll from the flanges to a point where, in its rotation, it will no longer contact with the flanges but in which the end of the roll still lies within the circle of the flanges.
- In testimony whereof I have signed my name to this specification.
- FREDERICK M. FURBER.
